CLAIM

I claim the ornamental design for a vessel with sleeve and lid, as shown and described.

DESCRIPTION

FIG. 1 is a top perspective view of a vessel with sleeve and lid.

FIG. 2 is a bottom perspective view thereof.

FIG. 3 is a front view thereof, the rear view being a mirror image.

FIG. 4 is a right side elevation view thereof, the left side elevation view being a mirror image.

FIG. 5 is a top plan view thereof; and,

FIG. 6 is a bottom view thereof.

The broken lines shown depict portions of the vessel with sleeve and lid that form no part of the claimed design.
